[57] **CLAIM**

The ornamental design for a food warmer, as shown
and described.

DESCRIPTION

FIG. 1 is a right, front and top perspective view of a
food warmer showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.
The cord in FIGS. 1-7 is bracketed for ease of illus-
tration.

FIG. 1

FIG. 2

FIG. 3

*FIG. 4**FIG. 5**FIG. 6*

FIG. 7
